UNITED STATES PATENT OFFICE.

WILLIAM FREDERICK BOAST, OF COLBY, KANSAS.

JEWEL-SETTER.

SPECIFICATION forming part of Letters Patent No. 746,444, dated December 8, 1903.

Application filed April 1, 1903. Serial No. 160,555. (No model.)

To all whom it may concern:

Be it known that I, WILLIAM FREDERICK BOAST, a citizen of the United States, and a resident of Colby, in the county of Thomas and State of Kansas, have invented a new and Improved Jewel-Setter, of which the following is a full, clear, and exact description.

The invention relates to watchmakers' tools; and its object is to provide a new and improved jewel-setter which is simple and durable in construction, very effective in operation, and arranged to permit a jeweler to accurately and quickly set the roller-jewel in correct position in the roller-table of the watch-balance.

The invention consists of novel features and parts and combinations of the same, as will be more fully described hereinafter and then pointed out in the claims.

20 A practical embodiment of the invention is represented in the accompanying drawings, forming a part of this specification, in which similar characters of reference indicate corresponding parts in all the views.

25 Figure 1 is a plan view of the improvement, showing the balance-wheel in position. Fig. 2 is a side elevation of the same. Fig. 3 is an enlarged plan view of the improvement, and Fig. 4 is an enlarged side elevation of the same.

The body-plate A of the jewel-setter is provided at one end with a suitable handle B, adapted to be taken hold of by the jeweler for conveniently holding the tool, and on the 35 said body-plate are arranged legs C for supporting the plate a suitable distance over the work-table. In the front side of the body-plate A is arranged a vertically-disposed V-shaped groove A' for the reception of the 40 roller-jewel, held in place in the said groove by a flat spring D, secured at one end by a screw E or other means to the front edge of the body-plate A. The spring D is adapted to be opened by a cam F, having its shaft F' 45 journaled in suitable bearings on the plate A, and on the shaft F' is secured a handle F² under the control of the jeweler to turn the shaft and the cam F so as to engage the peripheral face of the cam with the inner face 50 of the spring D to swing the latter outward to permit of conveniently placing the roller-

jewel in the groove A'. When this has been done, then the handle F² is turned to bring the flat portion of the cam F opposite the inner face of the spring D to allow the latter to 55 close by its own resiliency, thereby engaging the free end of the spring with the roller-jewel.

In the body-plate A is arranged an elongated aperture A² in transverse alinement 60 with the groove A' and adapted to receive the staff of the balance-wheel, as indicated in dotted lines in Fig. 3. On opposite sides of this aperture A² are arranged clamping-arms G and G' for engaging opposite sides of 65 the roller-table of the watch-balance, and the inner edges of the said clamping-arms G and G' are beveled to draw the roller-table firmly down onto the top face of the body-plate A, so that the roller-table is in proper 70 position for receiving the roller-jewel held in the vertical groove A'. The clamping-arms G and G' are fulcrumed at G² and G³ on the top plate A, and the fulcrum ends of the said clamping-arms are connected with each other 75 by gear-teeth G⁴ G⁵ to cause the clamping-arms G and G' to move in unison. The clamping-arm G' is provided with a handle G⁶, under the control of the jeweler, to open and close the 80 clamping-arms to disengage or engage the roller-table of the watch-balance. The fulcrum ends of the clamping-arms G and G' are pressed on by the free ends of flat springs H and H', secured to the rear side of the body-plate A, and the said springs serve to 85 press the clamping-arms G and G' in contact with the roller-table, so as to hold the same in position. The fulcrum end of the clamping-arm G' is provided with a flat face G⁷, engaged by the spring H' at the time the 90 clamping-arms G and G' are in an open position, as shown in Fig. 3, so that the clamping-arms are held in this open position. When the jeweler swings the arm G⁶ forward, then the clamping-arms G and G' move into a 95 closed position and the flat face G⁷ moves out of engagement with the spring H', so that the springs H and H' finally press the fulcrum ends of the clamping-arms G and G' to swing the latter toward each other, and thereby in firm engagement with the roller-table. 100 Now by the arrangement described the jew-

eler is enabled to conveniently insert the roller-jewel and to place the balance-wheel in proper position for receiving the jewel.

Having thus described my invention, I claim 5 as new and desire to secure by Letters Patent—

1. A jewel-setter comprising a handled body, a plate formed in one side edge with a vertical groove, for the reception of the jewel, 10 a spring on the said side edge, extending across the groove, to engage and hold the roller-jewel in place, and a pair of coacting spring-pressed clamping-arms on the top of the body-plate, for engaging the roller-table 15 at opposite sides, as set forth.

2. A jewel-setter comprising a handled body, a plate formed in one side edge with a vertical groove, for the reception of the jewel, a spring on the said side edge, extending 20 across the groove, to engage and hold the roller-jewel in place, and a pair of coacting spring-pressed clamping-arms on the top of the body-plate, for engaging the roller-table 25 at opposite sides, the inner edges of the said clamping-arms being beveled, as set forth.

3. A jewel-setter having a plate, formed with an aperture, for the reception of the balance-staff, a pair of spring-pressed clamping-arms, fulcrumed on the said plate and extending 30 on opposite sides of the aperture, to engage the roller-table from opposite sides and means for holding the jewel in position, as set forth.

4. A jewel-setter having a plate provided 35 with means for receiving and holding a jewel, the said plate being formed with an aperture, for the reception of a balance-staff, and a pair of spring-pressed clamping-arms, fulcrumed on the said plate and extending on 40 opposite sides of the aperture, to engage the roller-table from opposite sides, the inner edges of the said clamping-arms being beveled, to draw the roller-table down onto the top of the said plate, as set forth.

45 5. A jewel-setter having a plate, formed with an aperture, for the reception of a bal-

ance-staff, a pair of spring-pressed clamping-arms, fulcrumed on the said plate and extending on opposite sides of the aperture, to engage the roller-table from opposite sides, 50 the clamping-arms being pivoted on the top of the plate, means connecting the clamping-arms with each other, to move the clamping-arms in unison, the said plate being provided with a groove for the reception of the jewel, 55 and means for holding the jewel in place in the groove, as set forth.

6. A jewel-setter having a plate, formed with an aperture, for the reception of a balance-staff, a pair of spring-pressed clamping- 60 arms, fulcrumed on the said plate and extending on opposite sides of the aperture, to engage the roller-table from opposite sides, the clamping-arms being pivoted on the top of the plate, means connecting the clamping- 65 arms with each other, to move the clamping-arms in unison, one of the clamping-arms having a handle, under the control of the jeweler and means for holding the jewel in position, as set forth.

7. A jewel-setter, comprising a plate formed in one side edge with a groove for the reception of the jewel, a spring on the said side edge extending across the groove, to hold the jewel in position, a cam for moving the spring 75 outward to permit of conveniently placing the jewel in the groove, the plate being formed with an aperture for the reception of the balance-staff, a clamping device on the plate for holding the roller-table in position to receive the jewel, a handle at one end of the plate, and legs arranged on the plate for supporting the latter a suitable distance over the work-table, as set forth.

In testimony whereof I have signed my 85 name to this specification in the presence of two subscribing witnesses.

WILLIAM FREDERICK BOAST.
